KEY ACTUATED LOCKING BOLT

Herman H. Kistner, Baltimore, Md., assignor to
 Kistner Lock and Appliance Company, Baltimore, Md., a corporation of Maryland

Application September 18, 1935, Serial No. 41,115

10 Claims. (Cl. 70—90)

This invention relates to sliding bolts of the push-pull type commonly used for securing swinging and sliding doors, closets, drawers, windows and other closures, and aims to provide for locking it the same in both retracted and projected positions.

The invention further aims to improve bolt locks of the multiple tumbler type for all purposes for which a key actuated lock is desirable, and particularly to safeguard such locks from being jimmied or forced by any means readily available to unauthorized persons.

The invention enables a strong and secure bolt lock to be produced at low cost, applicable to many purposes for which heretofore no adequate key actuated lock has been available.

Other objects and advantages of the invention appear in connection with the following description of two preferred forms or embodiments of the invention, illustrated in the accompanying drawing, wherein

Fig. 1 is a part sectional and part side view of a locking bolt illustrated as secured to the side of a door, window or other closure which swings or slides in a frame, the bolt being shown in locking position;

Fig. 2 is a longitudinal cross-section thereof on the line 2—2 in Fig. 1, looking in the direction of the arrows;

Fig. 3 is a cross section thereof on the line 3—3 in Fig. 1, showing the butt end of the bolt and key slot therein in elevation;

Fig. 4 is a transverse cross-section on the line 4—4 in Fig. 1, looking in the direction of the arrows;

Fig. 5 is a disassembled perspective view of the plunger, and shell; and

Fig. 6 is a vertical cross-section through a double hung window sash showing a mortise type bolt lock embodying the invention.

In the form of the invention illustrated in Figs. 1 to 5 inclusive, the body or housing 11 is provided with a stud 12 to seat in a corresponding hole drilled in the face of the door style, meeting rail, or other movable part that is to carry it, and base flanges 13 whereby it may be secured against the face of the door or the like by screws if desired. The body is drilled lengthwise to receive the lock shell 14, which may be secured therein by means of a set screw 15. Such a housing body may be readily secured to any outwardly opening closure member that it is desired to lock by means of a sliding bolt mounted on its exterior, and when the closure is locked into its frame, the housing body cannot be removed without un-

locking it. No claim is made herein to the combination of housing body and stud with the sliding bolt, this feature of the invention being the subject-matter of my application Ser. No. 41,116, filed September 18, 1935.

The lock shell is hollow to receive the sliding bolt 16 and is slotted lengthwise and circumferentially as shown in Fig. 5 to receive the guiding and locking pin 17 which is driven into the bolt near its butt end. At the forward end of the housing is an inturned flange 18 which closes the end of the bore except for the hole through which the forward end of the bolt protrudes in projected or locking position. In the form shown in Fig. 6 this flange is on the end of the shell. The shell is provided with spaced openings 19, 20 for receiving the ends of the locking pins or discs 21, for locking the bolt in locking and retracted positions respectively.

These locking members 21 are mounted in cross slots 22 in the bolt body and are normally held in their outward positions with their ends projecting into one or the other of the openings 19, 20, by small coil springs 23 disposed in staggered holes drilled in the bolt body at the ends of the cross slots 22. These locking members or tumblers have openings through which the key 24 passes when inserted in the axial slot 25 in the butt end of the bolt, the dimensions of these openings cooperating with the nibs on the key for alining all the locking members with their ends flush with the bolt body when the key is inserted to permit manipulation of the bolt. Thus when the key is inserted in the bolt to its proper seat, the bolt can be moved endwise and rotated thereby, its movements being guided by the pin 17 working in the slot in the shell.

A coil spring 26 is arranged in the space between the flange 18 and a shoulder on the bolt adjacent its body to retract it when unlocked by the key and rotated so that the guide pin 17 is in alinement with the longitudinal portion 27 of the slot in the shell. A notch 28 is provided at the end of the transverse portion of the slot in the shell into which the spring 26 forces the pin 17 in the protruded or locking position of the bolt. Unless the mating key is in its proper place in the slot provided for it in the butt end of the bolt, the ends of the pins or discs 21 engage in one or the other of the opposite openings of the pairs 19, 20 in the shell to prevent the bolt from turning, thereby safeguarding the bolt against movement should an attempt be made to turn it by a false key, screw driver or like implement inserted in the key slot.

In the embodiment illustrated in Fig. 6 the shell 29, provided with a flange 30 on its end and containing the sliding bolt 16, locking pins or tumblers 21 and retracting spring 26, is mounted 5 in a split bushing 31 and pressed into a bored hole in one of the meeting rails 32 of a double hung sliding window. The opposite rail 33 is fitted with a suitable socket 34 to receive the end of the bolt when projected in locking position. Spaced projections 35 on the bushing secure it in place in the sash. The operation of the lock is the same as that shown in Figs. 1 to 5. No claim is made herein to the split bushing and mounting for the bolt lock, this feature of 10 the invention being the subject-matter of my application Serial No. 127,225, filed February 23, 1937.

The housing, shell and body portion of the bolt may be made accurately and cheaply by die-casting methods, and the key and pin discs are readily stamped from sheet metal, thereby enabling 20 the lock to be produced at minimum cost.

Modification of the shape and arrangement of the parts and changes in the dimensions to suit 25 different types of lock and places of use may be made without departing from my invention which is not restricted to the illustrative embodiments herein described.

I claim the following as my invention:

- 30 1. A bolt lock having a housing, a cylindrical bolt mounted therein for sliding and rotating movement, one end of said bolt being adapted for projection into a cooperating socket member in its locking position and the other end being grooved to receive a key, an abutment on said bolt spaced from its locking end, spring means 35 surrounding said bolt between said abutment and a fixed part of said housing for retracting said bolt from locking position, a transverse abutment 40 in said housing intermediate the ends of said bolt, said transverse abutment being spaced between said bolt abutment and grooved end of said bolt in unlocked position thereof, means on said bolt for engaging said transverse abutment in 45 locking position to retain it against pressure of said spring, rotation of said bolt serving to disengage said means from said transverse abutment to permit retraction of the bolt, and key actuated means carried by said bolt to lock it against rotation in its locking position.
- 50 2. A bolt lock having a housing, a cylindrical bolt mounted therein for sliding and rotating movement, one end of said bolt being adapted for projection into a cooperating socket member in its locking position and the other end being grooved to receive a key, an abutment on said bolt spaced from its locking end, spring means 55 surrounding said bolt between said abutment and a fixed part of said housing for retracting said bolt from locking position, a transverse abutment in said housing intermediate the ends of said bolt, said transverse abutment being spaced between said bolt abutment and grooved end of said bolt in unlocked position thereof, means on said bolt for engaging said transverse abutment in 60 locking position to retain it against pressure of said spring, rotation of said bolt serving to disengage said means from said transverse abutment to permit retraction of the bolt, a recess in said housing adjacent said key-receiving slot in said bolt, a transverse opening in said bolt intersecting said key-receiving slot and adapted to register with said housing recess in locking position, 65 and key-actuated means carried by said bolt to

engage said recess in locking position of said bolt and lock it against rotation.

3. A bolt lock having a cylindrical housing adapted for insertion in a corresponding recess in a frame member and having an internal flange 6 at one end and an opening to receive the bolt at the other end, a cylindrical bolt mounted therein for rotating and sliding movement, one end of said bolt projecting from the flanged end of said housing in locking position and the other being substantially flush with the open end of the housing in retracted position, the latter end of the bolt being slotted to receive a key, an abutment on said bolt spaced from its locking end, a coil spring surrounding said bolt between said abutment and the flange at the end of said housing, a transverse pin in said bolt near its slotted end, a groove in the wall of said housing remote from said spring, said groove being shaped to receive said pin and extending longitudinally and circumferentially to 20 permit lengthwise and turning movement of said bolt and terminating in a seat for retaining the bolt in locking position against the pressure of said spring, said seat being spaced lengthwise of said housing to avoid overlapping said spring in 25 any position of said bolt, and radially projecting means carried by said bolt for engaging said housing to prevent movement of the bolt, said means being retractable by the insertion of the proper key in said key slot to permit movement of said bolt by said key to unseat said pin from its seat.

4. A bolt lock having a cylindrical housing adapted for insertion in a corresponding recess in a frame member and having an internal flange at one end, a cylindrical bolt mounted therein for 35 rotating and sliding movement, one end of said bolt projecting from the flanged end of said housing in locking position and the other being substantially flush with the corresponding end of the housing in retracted position, the latter end 40 of the bolt being slotted to receive a key, an abutment on said bolt spaced from its locking end, a coil spring surrounding said bolt between said abutment and the flange at the end of said housing, a transverse pin in said bolt near its slotted 45 end, a groove in said housing to receive said pin, said groove extending longitudinally and circumferentially to permit lengthwise and turning movement of said bolt and terminating in a seat for retaining the bolt in locking position against 50 the pressure of said spring, longitudinally and circumferentially spaced recesses in said housing, and radially projecting means carried by said bolt for engaging said housing recesses to prevent movement of the bolt, said means being retractable by the insertion of the proper key in said key slot to permit movement of said bolt by said key to locking and retracted positions, respectively.

5. A bolt lock having a cylindrical housing 60 adapted for insertion in a corresponding recess in a frame member, a cylindrical bolt mounted therein for rotating and sliding movement, one end of said bolt projecting from the adjacent end of said housing in locking position and the other being substantially flush with the corresponding end of the housing in retracted position, the latter end of the bolt being slotted to receive a key, an abutment on said bolt spaced from its locking end, a coil spring surrounding said bolt between said abutment and the locking end 65 of said bolt and abutting against a fixed part of said housing, said housing having a smooth wall free from openings of greater than 45° subtended angle surrounding said spring in all po- 70 75

sitions of said bolt to avoid fouling of said spring therewith, a transverse pin in said bolt near its slotted end, a groove in said housing to receive said pin, said groove extending longitudinally and circumferentially to permit lengthwise and turning movement of said bolt and terminating in a seat for retaining the bolt in locking position against the pressure of said spring, and radially projecting means carried by said bolt 10 for engaging said housing to prevent rotation of the bolt, said means being retractable by the insertion of the proper key in said key slot to permit rotation of said bolt by said key to unseat said pin from its seat.

15 6. A cylindrical shell for a sliding and rotating locking bolt carrying locking tumblers, said shell having an internal flange at one end and open at the opposite end to receive the bolt, two pairs of diametrically opposed openings in said shell, 20 said pairs of openings being spaced axially and circumferentially with respect to each other and each being the same size and adapted to receive the locking tumblers carried by said bolt to lock it against rotation and axial movement in either 25 of its positions, said shell having a lengthwise extending groove terminating in a circumferentially offset portion to receive a guiding and locking pin on said bolt.

7. A bolt lock having a housing, a cylindrical bolt mounted therein for sliding and rotating movement, one end of said bolt being adapted for projection into a cooperating socket member in its locking position and the other end being grooved to receive a key, an abutment on said 35 bolt spaced from its locking end, spring means surrounding said bolt between said abutment and a fixed part of said housing for retracting said bolt from locking position, a pin and groove connection between said bolt and housing spaced 40 from said fixed part and removed from said spring means whereby the latter cannot overlap said groove in any position of said bolt, said groove extending longitudinally and circumferentially to permit lengthwise and turning movement 45 of said bolt, the circumferential portion of said groove cooperating with said pin to retain the bolt in locking position against the pressure of said spring means whereby rotation of said bolt serves to engage and disengage said cooperating 50 retaining means, and key actuated means carried by said bolt to lock it against rotation in its locking position.

8. A bolt lock comprising a cylindrical bolt mounted for sliding and rotating movement in a 55 housing having a bore to receive it, the ends of said bore being open, a lengthwise and circumferentially extending groove in one of said members and a follower fixed to the other member and engaging in said groove, said bolt having axially 60 spaced transverse slots extending through it from side to side and a key slot extending from its butt

end and intersecting said transverse slots, and said body having correspondingly shaped diametrically opposed axially and circumferentially spaced recesses in its wall to register with said transverse slots in the side of said bolt in locking 5 and retracted positions thereof, transversely disposed means cooperating with said recesses and slots to prevent endwise movement and rotation of said bolt except when said means are rendered ineffective by the insertion of the proper key in 10 said key slot.

9. A bolt lock having a cylindrical housing adapted for insertion in a corresponding recess in a frame member, a cylindrical bolt mounted therein for rotating and sliding movement, one 15 end of said bolt projecting from said housing in locking position and the other being substantially flush with the corresponding end of the housing in retracted position, the latter end of the bolt being slotted to receive a key, an abutment on said 20 bolt spaced from its locking end, a coil spring surrounding said bolt between said abutment and one end of said housing, a pin and groove connection between said bolt and the other end of said housing, said groove extending longitudinally and circumferentially in the direction away from said 25 spring to permit lengthwise and turning movement of said bolt, the circumferential portion of said groove being removed from said spring in all 30 positions of said bolt and cooperating with said pin to retain the bolt in locking position against the pressure of said spring whereby rotation of said bolt serves to engage and disengage said cooperating 35 retaining means, and radially projecting means carried by said bolt for engaging said housing to prevent rotation of the bolt, said means being retractable by the insertion of the proper key in said key slot to permit rotation of said bolt by said key to unseat said pin from its seat.

10. A bolt lock comprising a cylindrical bolt 40 mounted for sliding and rotating movement in a housing having a bore to receive it, a lengthwise and circumferentially extending groove in one of said members and a follower fixed to the other member and engaging in said groove, said bolt 45 having axially spaced transverse slots extending through it from side to side and a key slot extending from its butt end and intersecting said transverse slots, and said body having diametrically opposed axially and circumferentially spaced 50 recesses in its wall to register with said slots in the side of said bolt in locking and retracted positions thereof, spring pressed slides mounted in said axially spaced slots and normally projecting into one or the other of said spaced recesses, said recesses and slides cooperating to prevent endwise movement and rotation of said bolt except when rendered ineffective by the insertion of the proper key in said key slot.
